UNITED STATES PATENT OFFICE

REUBEN B. BENJAMIN, OF CHICAGO, ILLINOIS, ASSIGNOR TO BENJAMIN ELECTRIC MANUFACTURING COMPANY, OF DES PLAINES, ILLINOIS, A CORPORATION OF ILLINOIS

ELECTRIC IRON CONSTRUCTION

Application filed July 12, 1929. Serial No. 377,863.

My invention relates to electric iron construction.

One of the objects of my invention is to provide a thermostatic control for the heating element of the type in which the switch mechanism is located in the handle which will be positive and accurate in action.

A further object is to provide such a construction in which the positiveness and accuracy is secured by the use of a thermostatic element of the extensible type, as distinguished from the flexible type.

A further object is to provide a thermostatic control of the type in which the switch mechanism is located in a manner which will require a relatively small amount of work to be done by the thermostatic element to effect the operation of the switch.

A further object is to provide a construction of the type indicated above in which the ease of operation is attributable to an easily operated latch controlled by the thermostatic element.

A further object of my invention is to provide a thermostatic control for a switch located in the handle of the iron in which improved antifriction means are provided for guiding the switch-operating member and assisting to retain it in "on" position.

Further objects will appear from the description and claims.

In the drawings, in which an embodiment of my invention is shown—

Figure 1 is a side elevation of an electric iron embodying my invention;

Fig. 2 is a section on the line 2—2 of Fig. 3;

Fig. 3 is a front view of the iron;

Fig. 4 is a section on the line 4—4 of Fig. 1;

Fig. 5 is a section on the same plane as

Fig. 2 showing the switch in "off" position;

Fig. 6 is a section on the line 6—6 of Fig. 1;

Fig. 7 is a section on the line 7—7 of Fig. 5;

and

Fig. 8 is a perspective view of a cam for determining the temperature at which the switch will be moved to "off" position.

Referring to the drawings in detail, the construction shown comprises an electric iron having a body portion 1 containing the heating element 2, a handle 3 of insulating mate-

rial, a thermostatic switch construction for controlling the circuit for the heating element 2 comprising a switch blade 4, a blade-shifting spring 5, a spring-shifting bar 6 mounted in the handle 3 for longitudinal movement 53 therein, a coil tension spring 7 tending to pull the spring-shifting bar 6 to the left as viewed in Figs. 2 and 5, a roller 8 for engaging the notch 9 in said spring-shifting bar 6 to assist in retaining said spring-shifting bar 6 against 60 movement when latched and to guide it in its movement when released to cause the engaging portion of the bar 6 to travel in a substantially circular path whereby the initial movement of said engaging portion will 65 have a substantially vertical component, a latch 10 for said spring-shifting bar 6 which, when in latching position, serves to resist movement of the bar 6 vertically, means for shifting the roller 8 with respect to the latch 70 10 to vary the point of relation of the spring-shifting bar 6 comprising a rotatable cam 11, and a thermostatic element comprising a heat extensible bar 12 lying substantially in a horizontal plane and having an actuating 75 portion 13 movable substantially in a horizontal plane for controlling the latch 10.

Before describing the construction in detail I will briefly outline the operation. The current is supplied to the separable connector 80 member 14 by means of suitable conductors, not shown. If the switch is in the position shown in Fig. 5, the spring-shifting bar 6 is pushed to the right by means of the push button 15 until the roller 8 enters the notch 9 in the lower edge of the bar, the upper end of the hooked latch member 10 being shifted slightly to the right during this movement until the catch portion 16 on the bar 6 slips underneath the hook portion 17 on the latch 10 whereupon the coil compression spring 18 causes the latch 10 to snap to the left to bring the hook portion 17 above the catch portion 16 to retain the spring-shifting bar 6 in latched position. This movement of the spring-shifting bar 6 to the right moves the end of the blade-shifting spring 5 to the right past the dead center of the switch blade 4 causing the switch blade 4 to snap in position between the separated contacts 19. This movement of 100

the switch to "on" position causes current to be supplied to the heating element 2 of the iron. As the iron heats up, the left-hand end 13 of the heat extensible bar 12 moves to the left causing the latch 10 to move about its pivot 20 until the hook 17 at the upper end of the latch disengages the catch 16 on the spring-shifting bar 6. Thereupon the spring-shifting bar 6 snaps to the left under the 10 action of the coil tension spring 7 to the position shown in Fig. 5. During this movement the lower end of the blade-shifting spring 5 is again moved past the dead center of the switch blade causing the switch blade 4 to move out from between the spaced contact members 19 to break the circuit with a snap movement.

If the action of the blade-shifting spring 5 should not be sufficient to free the switch 20 blade 4 at once from the spaced contacts the lug 21 on the spring-shifting bar 6 will strike the blade-shifting spring 5 giving it a quick impetus which will quickly free the switch blade 4 from engagement with spaced contacts 19.

As the user continues to use the iron, it will gradually cool down causing the left-hand end 13 of the heat extensible bar 12 to move to the right. This movement of the end 13 30 of the heat extensible bar 12 to the right permits the upper end of the latch 10 to move to the left under the action of the coil compression spring 18. As soon as the iron has cooled down to a point below which it would 35 not do good work the user again operates the push button 15 to push the spring-shifting bar 6 from the position shown in Fig. 5 to the position shown in Fig. 2, during which movement the latch member 10 will again 40 engage the catch member 16 to hold the switch in "on" position until it is again released by the action of the heat extensible bar 12.

In order to vary the point of release of the spring-shifting switch controlling member 6 45 the retaining roller 8 is movably mounted on a spring bracket 22, the position of which spring bracket 22 is controlled by a rotatable face cam 11. This cam, as shown, determines 3 positions for the retaining roller 8 corresponding to high temperature, medium temperature and low temperature. The farther 50 the retaining roller 8 is to the right, as viewed in Fig. 5, the greater will be the movement of the latch 10 necessary to release the switch-controlling bar 6 and the higher will have to be the temperature of the iron before this release is effected. Consequently, the high spot 55 23 on the cam corresponds to the high temperature for release, the two intermediate portions 24 of the cam corresponding to the medium temperature and the low portion 25 of the cam corresponding to the low temperature. This cam is rotatably mounted in the front standard 26 or handle support and is 60 operated by means of a thumb piece 27 having

indicia 28 thereon to indicate the degree of temperature at which the switch will be released.

In order to enable a factory adjustment to be made the catch member 16 on the switch controlling bar 6 is adjustably mounted on this bar 6 by means of a pair of screws 28 extending through slots in this catch member and threaded into the switch controlling bar. This catch member 16 is set at the proper position at the factory and is not thereafter to be disturbed by the user, the adjustment by the user being effected by means of the thumb piece 27. It may sometimes be desirable to release the switch controlling bar 6 70 without waiting for the thermostatic means to effect this release and for this purpose I provide a lever 29 (Figs. 5, 6 and 7) pivotally mounted at 30 on the lower half of the insulating handle 3 having one arm extending in position to engage the upper end of the latch lever 10 and having its other end extending out beyond the contour of the handle, as shown in Fig. 6, in a position for convenient operation by the thumb of the user. To release the latch manually this extended portion 31 of the lever is passed inwardly by the thumb pushing the upper end of the latch 10 to the right as viewed in Fig. 5 to release the catch member and permit the spring to 80 throw the switch to "off" position.

The two halves of the handle may be held together by means of screws 32 extending through the handle supports 26 and 33, these screws 32 thus serving also to secure the handle to these supports. The right-hand end of the switch-actuating bar 6 is held in proper position and guided in its movement by means of a roller 34 with which the upper edge of the right-hand end of the switch-controlling bar 6 engages. The movement of this switch-controlling bar to the left may be limited by the engagement of the upward extension 35 of the bar 6 with the roller 34.

The latch lever 10 may be pivotally mounted at 20 on a supporting bracket 36 secured to the body portion of the iron. The spring 5 which serves as a blade-shifting spring also serves to hold the right-hand end of the spring-controlling bar 6 in engagement with the roller 34.

While I have shown but one form of my invention, various forms will be obvious to those skilled in the art and consequently this invention is to be limited only by the scope of the appended claims and the prior art.

I claim:

1. An electric iron construction comprising a body portion, an elongated handle and thermostatic switch construction for controlling the circuit comprising a switch blade, a blade-shifting member mounted for general longitudinal movement with respect to said handle, an actuating spring acting on said blade-shifting member, a latch for holding 125

5 said blade-shifting member against the action of said actuating spring, and a thermostatic element comprising a heat extensible elongated member lying substantially in a horizontal plane and having an actuating portion movable substantially in a horizontal plane for controlling said latch, said latch comprising an oscillatable member extending from said heat extensible member to said blade-shifting member and pivotally mounted at a point between said heat extensible member and blade-shifting member.

10 2. An electric iron construction comprising a body portion, an elongated handle and thermostatic switch construction for controlling the circuit comprising a switch blade, a blade-shifting member mounted for general longitudinal movement with respect to said handle, an actuating spring acting on said blade-shifting member, and thermostatic controlling means whereby said blade-shifting member is released for movement, and means for guiding a portion of said blade-shifting member so that when released it must move initially in a direction having a substantial vertical component, said guide means comprising a roller, said blade-shifting member having an abutment portion engaging said roller.

15 3. An electric iron construction comprising a body portion, an elongated handle and thermostatic switch construction for controlling the circuit comprising a switch blade, a blade-shifting member mounted for general longitudinal movement with respect to said handle, an actuating spring acting on said blade-shifting member, and thermostatic controlling means whereby said blade-shifting member is released for movement, and means for guiding a portion of said blade-shifting member so that when released it must move initially in a direction having a substantial vertical component, said guide means comprising a roller, said blade-shifting member having an abutment portion engaging said roller, said roller being adjustably mounted to vary the point of release of the blade-shifting member.

20 4. An electric iron construction comprising a body portion, an elongated handle and thermostatic switch construction for controlling the circuit comprising a switch blade, a blade-shifting member mounted for general longitudinal movement with respect to said handle, an actuating spring acting on said blade-shifting member, and thermostatic controlling means whereby said blade-shifting member is released for movement, and means for guiding a portion of said blade-shifting member so that when released it must move initially in a direction having a substantial vertical component, said guide means comprising a roller, said blade-shifting member having an abutment portion engaging said roller, said guide means being

adjustably mounted to vary the point of release of the blade-shifting member.

25 5. An electric iron construction comprising a body portion, an elongated handle and thermostatic switch construction for controlling the circuit comprising a switch blade, a blade-shifting member mounted for general longitudinal movement with respect to said handle, an actuating spring acting on said blade-shifting member, and thermostatic controlling means whereby said blade-shifting member is released for movement, and means for guiding a portion of said blade-shifting member so that when released it must move initially in a direction having a substantial vertical component, said thermostatic controlling means comprising a latch which in latching position serves to resist said initial vertical movement.

30 6. An electric iron construction comprising a body portion, an elongated handle and thermostatic switch construction for controlling the circuit comprising a switch blade, a blade-shifting member mounted for general longitudinal movement with respect to said handle, an actuating spring acting on said blade-shifting member, and thermostatic controlling means whereby said blade-shifting member is released for movement, and means for guiding a portion of said blade-shifting member so that when released it must move initially in a direction having a substantial vertical component, said thermostatic controlling means comprising a latch which in latching position serves to resist said initial vertical movement, and manual means for releasing said latch independently of the action of the thermostatic means.

35 7. An electric iron construction comprising a body portion, an elongated handle and thermostatic switch construction for controlling the circuit comprising a switch blade, a blade-shifting member mounted for general longitudinal movement with respect to said handle, an actuating spring acting on said blade-shifting member, a latch for holding said blade-shifting member against the action of said actuating spring, and a thermostatic element comprising a heat extensible elongated member lying substantially in a horizontal plane and having an actuating portion movable substantially in a horizontal plane for controlling said latch, said latch comprising an oscillatable member extending from said heat extensible member to said blade-shifting member and pivotally mounted at a point between said heat extensible member and blade-shifting member, and a member for supporting the handle on the body portion secured adjacent one end of the handle, said oscillatable member extending alongside and adjacent said supporting member.

40 8. An electric iron construction comprising a body portion, an elongated handle, and

- a thermostatic switch construction for controlling the circuit comprising a contact-controlling member mounted for general longitudinal movement with respect to said handle, an actuating spring acting on said circuit-controlling member, and thermostatic controlling means whereby said controlling member is released for movement, and means for guiding a portion of said circuit-controlling member so that when released it must move initially in a substantially circular path, said guide means comprising a roller, said circuit-controlling member having an abutment portion engaging said roller.
9. An electric iron construction comprising a body portion, an elongated handle, and a thermostatic switch construction for controlling the circuit comprising a contact-controlling member mounted for general longitudinal movement with respect to said handle, an actuating spring acting on said circuit-controlling member, and thermostatic controlling means whereby said controlling member is released for movement, and means for guiding a portion of said circuit-controlling member so that when released it must move initially in a substantially circular path, said guide means comprising a roller, said circuit-controlling member having an abutment portion engaging said roller, said roller being adjustably mounted to vary the point of release of said contact-controlling member.
10. An electric iron construction comprising a body portion, an elongated handle, and a thermostatic switch construction for controlling the circuit comprising a contact-controlling member mounted for general longitudinal movement with respect to said handle, an actuating spring acting on said circuit-controlling member, and thermostatic controlling means whereby said controlling member is released for movement, and means for guiding a portion of said circuit-controlling member so that when released it must move initially in a direction having a substantial vertical component, said guide means being adjustably mounted to vary the point of release of said contact-controlling member.
11. An electric iron construction comprising a body portion, an elongated handle, a thermostatic switch construction for controlling the circuit comprising a switch blade, a blade-shifting spring, a spring-shifting bar mounted in said handle for general longitudinal movement with respect thereto, an actuating spring acting on said spring-shifting member, a roller for engaging said spring-shifting bar to assist in retaining said spring-shifting bar against movement when latched and to guide it in its movement when released, to cause the engaging portion of the bar to travel in a substantially circular path whereby the initial move-
- ment of said engaging portion will have a substantial vertical component, a latch for said spring-shifting bar which when in latching position serves to resist movement of the bar having a substantial vertical component, means for shifting said roller with respect to said latch to vary the point of release of the spring-shifting member, comprising a rotatable cam, a thermostatic element comprising a heat extensible bar lying substantially in a horizontal plane and having an actuating portion movable substantially in a horizontal plane for controlling said latch, said latch comprising an oscillatable member extending from said heat extensible member to said spring-shifting member and pivotally mounted at a point between said heat extensible member and spring-shifting member.
- In witness whereof I have hereunto subscribed my name.
